AMUSEMENT DEVICE

Mordicha Margolish, Hawthorne, Calif., assignor
to National Merchandising Company Ltd.,
Santa Monica, Calif., a corporation

Application August 25, 1933, Serial No. 686,744

18 Claims. (Cl. 273—138)

This invention relates to an amusement device and relates more particularly to a coin controlled vending machine or amusement device. It is a general object of this invention to provide a coin controlled amusement device that is attractive and that is amusing and entertaining to operate or play.

Another object of the invention is to provide a coin controlled amusement device in which the player may use his skill in attempting to selectively win one or more attractively displayed articles of merchandise.

It is another object of the invention to provide an amusement device that includes a part that may simulate or represent any suitable object and that is movable across a table carrying the displayed articles or prizes, and a manual control whereby the player may partially govern the direction of movement of the said part in an attempt to push or displace a selected article from the table to win the same.

It is another object of the invention to provide an amusement device of the character mentioned that is entirely automatic in operation after the player has inserted a suitable coin and need not be manually controlled unless the player desires to alter the course of movement of the prize moving part to push or move a selected article from the table.

It is another object of the invention to provide a coin controlled amusement device of the character mentioned that is fully tamper-proof so that its operation cannot be interfered with or altered and so that the displayed articles or prizes cannot be surreptitiously shifted or stolen.

It is another object of the invention to provide an amusement device of the character mentioned that includes a discharge chute for carrying the won articles or prizes from the table, and novel and improved automatic closures for the chute that are related to the operating circuit of the device in a manner to prevent succeeding operation of the device if an attempt is made to hold the closures open or to reach into the compartment in which the prizes or articles are displayed.

It is a further object of the invention to provide a coin controlled amusement device or vending machine that is simple and inexpensive of manufacture and operation.

Further objects and features of the invention will be best and fully understood from the following detailed description of a typical form and application of the invention, throughout which

description reference is had to the accompanying drawings, in which:

Fig. 1 is a front elevation of the device provided by the present invention with a portion of the cabinet front broken away to show the interior. Fig. 2 is a side elevation of the device with a portion of the cabinet broken way to illustrate the interior. Fig. 3 is an enlarged transverse detailed sectional view taken as indicated by line 3—3 on Fig. 1. Fig. 4 is an enlarged vertical detailed sectional view taken substantially as indicated by line 4—4 on Fig. 3. Fig. 5 is a vertical detailed sectional view taken substantially as indicated by line 5—5 on Fig. 4. Fig. 6 is an enlarged fragmentary detailed sectional view of the rotatable mounting for the table showing the table operating pawl in operating position. Fig. 7 is a vertical detailed sectional view taken substantially as indicated by line 7—7 on Fig. 4. Fig. 8 is an enlarged fragmentary horizontal detailed sectional view taken substantially as indicated by line 8—8 on Fig. 7, and Fig. 9 is a diagrammatic wiring diagram of the electrical circuit and associated parts of the device.

The vending machine or amusement device provided by the present invention includes generally, a cabinet 10 having a discharge or delivery chute 11 for the prizes, a rotatable table 12 in the cabinet 10 for carrying the articles of merchandise or prizes, a part 13 movable across the table 12 and operable to push or displace articles into the chute 11, a coin controlled power means 14, means 15 operable by the power means 14 for moving the part 13 across the table 12, a manual control 16 for governing the direction of movement of the part 13, means 17 operable by the power means 14 for rotating the table 12, automatic closure means 18 for the chute 11 governed or operated by the power means 14, and means 19 for stopping operating of the machine at the end of its cycle.

The cabinet 10 is provided to hold or contain the various parts of the machine and may be varied considerably in construction etc., without departing from the principles of the invention. In the form of the invention illustrated in the drawings, the cabinet 10 is rectangular and has a closed lower portion and an upper portion provided with a front and sides 20 of transparent material. A horizontal partition 21 is provided in the cabinet 10 to separate its upper and lower portions. The upper portion of the cabinet provided with the transparent front and sides 20 is provided to hold the prizes or displayed articles and the movable part 13. The rear wall 22 of

the cabinet may be formed of wood, or the like, and its upper portion within the upper part of the cabinet may be provided with a reflector or mirror 23. The sides or walls 24 of the lower portion of the cabinet 10 may be formed of wood, or the like, and the front wall is preferably provided with a removable panel 25. A top 26 closes the upper end of the cabinet. A suitably shaded lamp 27 is shown within the upper portion of the cabinet 10 to illuminate the display table 12 and the adjacent parts.

A round vertical or transverse opening 28 is provided in the partition 21. The opening 28 is preferably comparatively large in diameter to leave practically the entire upper surface of the table 12 exposed. The opening 28 is spaced some distance rearwardly from the front wall of the cabinet, while its rear edge may be adjacent the back 22. The chute 11 is provided to deliver the articles pushed from the table 12 to the player at the front of the cabinet 10. An opening 30 in the partition 21 communicates with the upper end of the chute 11 and the chute extends downwardly and outwardly toward a side of the cabinet. An opening 31 is provided in a lower corner of the panel 25 and communicates with the lower portion of a chute 11. The lower portion of the chute 11 is vertical and has a closed bottom and sides. The opening 31 at the upper end of the chute 11 joins the opening 30 and is preferably spaced midway between the opposite sides of the cabinet.

The table 12 is provided to support or carry prizes or articles to be vended and is arranged within the cabinet 10 directly below the opening 28 in the cabinet partition. The table 12 is disc shaped and is larger in diameter than the opening 28. In the preferred construction, the table 12 is positioned immediately adjacent the under side of the partition 21 so that the articles on the table cannot pass or become caught between the table and the partition. A post 32 projects upwardly from the bottom of the cabinet to support the table 12. In accordance with the invention, the table 12 is rotatable and anti-friction means is provided to mount the rotatable table on the post 32. In the particular construction illustrated in the drawings, a cap 33 is provided on the upper end of the post 32 and a boss or socket member 34 is provided on the under side of the table and rotatably fits over the cap. An annular series of anti-friction balls 35 is arranged in registering grooves in the opposing surfaces of the cap 33 and member 34. The table 12, in being positioned at the opening 28 is readily visible through the transparent sides and front 20 of the cabinet and is arranged so that the articles cannot be displaced from it except when pushed off by the part 13.

The part 13 is movable forwardly across the table 12 toward the upper end of the chute 11 and is operable to push or move articles from the table into the chute. In accordance with the invention, the part 13 is moved or operated by the power driven means 15 and its direction of movement may be controlled to some extent by the manual means 16 so that the player may attempt to push a selected article from the table. It is a feature of the invention that the part 13 which is fully visible in the upper portion of the cabinet may represent or simulate any given object. In the particular case illustrated in the drawings, the part 13 represents or has the configuration of an elephant's head. The elephant's head faces forwardly and its trunk hangs substantially vertical.

to have its lower end clear the upper surface of the table 12 with but slight suitable clearance. The invention provides means to support the part 13 for movement forward to the opening 30 and for return movement to its normal position adjacent the back 22. A track or rail 36 is spaced above the partition 21 and has its forward end pivotally supported by a hanger 37. The rear end of the rail 36 is shiftable transversely or horizontally in an elongate slot 38 in a bracket 39. A trolley is movable longitudinally on the rail 36 and carries the elephant's head or part 13. The trolley comprises spaced plates 40 and spaced pairs of wheels 41 rotatably mounted between the plates. The spaced pairs of wheels 41 engage the upper and lower sides of the rail 36 to support the trolley for free longitudinal movement along the rail. The wheels 41 are preferably flanged to hold the trolley against swinging, etc. The part 13 is attached to or projects downwardly from a projection 41 on the lower side of the trolley. The rail 36 is sufficiently long to allow the trolley and part 13 to move forwardly to a position where the trunk or article engaging portion is at the periphery of the table 12 adjacent the opening 30.

The power means 14 is provided to operate the various mechanisms of the device and is coin controlled, that is, it is put into operation upon a coin being deposited in the device. The power means 14 comprises an electric motor 42 mounted on the bottom of the cabinet. The motor 42 rotates a horizontal shaft 43 through a speed reducing drive 44. The shaft 43 is supported by spaced posts 45 projecting upwardly from the bottom of the cabinet 10. Control switches A and B are provided in the energizing circuit C of the motor 42. The switch A may include a stationary contact 46 and a contact 47 on a lever arm 48. The lever arm 48 may be attached to a pivoted or rotatable shaft 49. The switch B includes a stationary contact 50 and a contact 51 on one arm of a lever 52. The lever 52 is carried by the rotatable shaft 53. The shafts 49 and 53 of the switches A and B are preferably positioned one adjacent the other or may be arranged in axial alignment. The switches A and B are preferably positioned adjacent the inner side of the panel 25 so as to be controlled or operated by a coin receiving slide 54. The coin receiving slide may be of well-known construction and normally projects forward from the panel 25. When a coin is put in its opening the slide 54 may be pushed inwardly so that the coin falls into or is received by an inclined coin chute 55. The coins are adapted to roll through the chute 55 and to be finally received in a locket box 56 having a door 57 in the panel 25. The invention provides means for controlling the movement of the coin through the chute 55 as will be subsequently described.

The coin slide 54 is operatively related with the switches A and B so that it opens one switch upon being moved inwardly so that the machine cannot be made to operate in the event the slide is held in. The switch A is normally closed, while the switch B is normally open, and upon the slide 54 being pushed in, the switch A is opened and the switch B is closed. In order to close the switch A to energize the motor 42, the slide 54 must be moved or operated to its out or normal position. In this manner the operation of the slide 54 to its in position without returning it to its normal position cannot energize the motor. The inner end of the slide 54 is adapted to strike an actuating pin 58 on the shaft 49 of the switch A and a simi-

lar pin 58 on the shaft of the switch B. This engagement opens the switch A and closes the switch B. The switch B thereafter remains closed until opened by the means 19 as will be subsequently described. When the slide 54 is moved to its out position or is permitted to return to its normal unactuated position, a hook 59 on the inner end of the slide engages the operating pin 57 of the switch A to pivot the shaft 59 to bring the contact 47 into engagement with the contact 46 and thus complete the energizing circuit of the motor 42. While I have illustrated and described the switches A and B in some detail, it is to be understood that any suitable type of switch may be substituted for the switches A and B.

The means 15 for moving the elephant's head or part 13 across the table 12 is automatically actuated by the power means 14. The means 15 operates to move the part 13 forwardly across the table to a point adjacent the opening 30 during the first part of the cycle of operation of the machine and then return the part 13 to its normal position adjacent the back 22. The means 15 includes two boom-like levers 60 and 61 pivotally mounted at their lower ends on the bottom of the cabinet 10. A lever or cam 62 is provided on the driven shaft 43 to cooperate with the lever 60 and a similar arm or cam 63 is provided on the shaft 43 to cooperate with the lever 61. The cams 62 and 63 are in different rotative positions so as to successively engage the levers 60 and 61. The levers 60 and 61 are operatively connected with the part 13. A flexible element 64 in the form of a cord or cable 35 has one end connected to the post 32 and extends over or through a pulley 65 on the outer end of the lever 60. From the pulley 65 the flexible element 64 passes downwardly through a pulley 66 at the upper end of the post 32 to a pulley 67 on the bottom of the cabinet adjacent the back 22. The flexible element 64 then extends upwardly to operate over a pulley 68 on the upper end of a cross arm 69 at the rear end of the rail 36 and then passes forwardly to operate over spaced pulleys 70 on a cross arm 71 at the forward end of the rail. The flexible element 64 extends from the lower pulley 70 rearwardly to have its end connected to the projection 41^a on the lower end of the trolley carrying the part 13. A flexible element 72 has one end attached to the post 32 and operates through a pulley 73 on the outer end of the lever 61. From the pulley 73 the flexible element 72 extends upwardly to a pulley 74 at the upper end of the post 32 and then passes downwardly to a pulley 75. The flexible element 72 extends upwardly from the pulley 75 and passes through a pulley 76 on the cross arm 69 and is then attached to the projection 41.

Upon energization of the motor 14 the shaft 43 is slowly turned in a direction to bring the cam 62 into engagement with the lever 60 so that the lever is pivoted downwardly. Downward pivoting of the lever 62 pulls the cord or flexible element 64 so that the elephant's head or part 13 is moved forwardly over the table 12. Downward pivoting of the lever 60 and forward movement of the part 13 of course causes pulling of the flexible element 72 which pivots the lever 61 upwardly. The cam 62 continues to pivot the lever 60 downwardly until the part 13 reaches a point at or adjacent the opening 30. The cam 63 then moves downwardly into engagement with the lever 61 to pivot the lever

61 downwardly. Downward pivoting of the lever 61 pulls the cord 72 to move the elephant's head or part 13 rearwardly and to pivot the lever 60 upwardly. The cam 63 continues to pivot the lever 61 downwardly until the lever 60, the lever 61 and the part 13 are returned to their normal inoperative positions illustrated throughout the drawings.

The manual means 16 for controlling the direction of movement of the elephant's head or part 13 is such that the player may shift the rail 36 horizontally and thus to a limited extent control the direction of movement of the part 13. The manual control means 16 includes a horizontal shaft 78 having its inner end supported by a post 79 and projecting forwardly through the panel 25. A suitable operating knob 80 is provided on the outer end of the shaft 78 for engagement by the player or operator. A second horizontal shaft 81 has its forward end supported by the post 79 and its rear end supported by a post 82. A speed reducing gear drive or operating connection 83 is provided between the shaft 78 and the shaft 81. A crank or arm 84 is provided on the rear end of the shaft 81. A block 85 is pivoted to the arm 84. Flexible elements in the form of cords or cables 86 are attached to the opposite ends of the block 85 and extend upwardly to connect the rear end of the pivoted rail 36. The flexible elements 86 operate over pulleys 87 carried by pivoted brackets 88. The pulleys 87 are urged against the flexible element by springs 89 to maintain suitable tautness in the flexible elements. It will be apparent how turning of the knob 80 results in turning of the arm 84 and lateral or horizontal pivoting of the rail 36. By suitably manipulating the knob 80 the player may direct the elephant's head or part 13 to engage a selected article on the table 12 so that the part 13 may push the article from the table.

The means 17 is operable to give the table 12 a partial turn near the end of the cycle of operation of the machine to change the positions of the articles on the table with respect to the elephant's head or part 13. The means 17 includes a series of teeth 90 projecting from the socket member 34 on the under side of the table 12. A pawl 91 is pivotally mounted on the upper end of a lever 92 and is adapted to cooperate with the teeth 90 to turn the table 12. A crank arm 93 is provided on the shaft 43 and is operatively connected with the lower arm of the lever 92 by a link 94. The crank arm 93 is related to the cams 62 and 63 to cause the pawl 91 to cooperate with the teeth 90 and give the table 12 a partial turn after the part 13 is returned to its normal position. A baffle 95 projects from the wall of the opening 28 inwardly over the table 12 to engage the merchandise or articles on the table and shift them toward the center of the table as it turns. The baffle 95 is operable to prevent the articles from gathering in groups on the table and from assuming positions immediately adjacent the edge of the table.

The closure means 18 normally closes the delivery chute 11 to prevent an object or a person's arm from being passed through the chute and constitutes a means for preventing tampering with the machine while it is in operation. The means 18 includes a closure or door 96 normally closing the opening 30 at the upper end of the chute 11. The door 96 is normally horizontal and is hinged at an edge so that it may swing downwardly into the chute 11 to allow objects that

may be pushed on to it by the part 13 to pass down through the chute. A spring 97 is connected with a projecting part of the door 96 to normally urge the door to the closed position. A latch 98 normally engages under a tongue at the upper edge of the door 96 to positively hold the door closed. An arm or cam 99 is provided on or connected with the latch 98. A lever 100 is pivoted on a suitable bracket 101 and is operable to release the latch 98 and open the door 96. The upper arm of the lever 100 has a cam part 102 which is adapted to cooperate with the cam 99 of the latch 98. A cam 103 is attached to the door 96 at its hinged mounting and is adapted to be engaged by the cam part 102 of the lever 100. A cam arm or cam 104 is provided on the driven shaft 43 and is adapted to engage the lower arm of the lever 100 to pivot the lever and cause its cam part 102 to first release the latch 98 and then cooperate with the cam 103 to swing the door 96 to its down or open position. The cam 104 remains in cooperation with the lever 100 a considerable time to fully open the door 96 and thereby allow the article or articles pushed on to the door by the part 13 to fall into the chute 11. The cam 104 is related to the cams 62 and 63 to provide for the opening of the door 96 after the elephant's head or part 13 has reached its fully forward position. A spring 105 may be connected with the lever 100 to return it to its normal position after the cam 104 has passed out of engagement with its lower arm. The spring 97 aids in returning the lever 100 and automatically closes the door 96 whereupon the latch 98 again assumes its latching engagement with the door. It is a feature of the invention that the closure means 18 provides a lower closure or door 106 extending across the lower portion of the chute 11. The door 106 is pivoted at one corner as at 107 and extends through a slot 108 in the wall of the chute to normally close off the inclined portion of the chute from its open lower portion. A lever 109 is provided to normally hold the door 106 closed and to operate the door to its open position. The lever 109 has an upper arm 110 which engages between the inner edge of the door 106 and a vertical post 111 to normally hold the door in its closed position. A flexible element in the form of a chain 112 operatively connects the lever arm 110 with the door 106. There is some slack in the chain 112 so that the end of the lever arm 110 may be disengaged from between the door 106 and the post 111 before the chain 112 is tightened and pulls the door open. A cam 113 is provided on the shaft 43 and is operable to engage the lower arm of the lever 109 to pivot the lever and cause opening of the door 106. The cam 113 is related to the cam 104 to cause opening of the door 106 subsequent to opening of the door 96 or during the closing of the door 96. A spring 114 is provided at the pivotal axis of the door 106 to automatically return the door to its closed position after disengagement of the cam 113 from the lever 109. It is a feature of the invention that the lower door 106 is related to the energizing circuit C of the motor 42 to cause the circuit to be broken in the event the door 106 is held open so that the machine cannot be again operated until the door 106 is permitted to close. Two switches M and N are provided in the circuit C. Each of these switches includes a fixed contact 115 connected by a common bus or lead 116 and a contact carried by a spring arm 117. The spring arm contacts 117 are connected by a common conductor 118. An extension or third arm 119 is provided on the lever 109 and is operable to engage the spring arm 117 of the switch M to normally hold the switch closed. The switch M remains closed due to the action of the lever extension 119 until the door 106 is opened by the cam 113 cooperating with the lever 109. When the cam 113 moves out of engagement with the lever 109 the door automatically closes, whereupon the lever extension 119 again engages the spring arm 117 to close the switch. In accordance with the invention, the cam 104 engages the contact arm or spring arm 117 of the switch N to close the switch prior to opening of the switch M and holds the switch N closed until the switch M is again closed by the lever extension 119. In this manner the operation of the device is continued during opening and closing of the door 106. If the player or any other person holds the door 106 open in an attempt to reach into the cabinet, or interfere with the operation of the device, the motor 42 will continue to operate only until the cam 104 moves out of engagement with the contact arm 117 of the switch N whereupon the circuit C is automatically broken which stops the operation of the device. It is to be understood that the door 96 is closed prior to opening of the door 106 and is latched by the latch 98 so that a person cannot reach into the upper portion of the cabinet when the door 106 is open. If the door 106 has been held open in an attempt to tamper with the device and is then released or permitted to close, the lever 109 automatically returns to its normal position to lock the door 106 in its closed position and to close the switch M so that operation of the device is resumed. It will be apparent that if a coin is introduced in the device by the slide 54 while holding the door 106 open, the motor 42 will not be energized as the switch M is left open due to the position of the lever 109.

The means 19 for stopping operation of the device automatically opens the energizing circuit C at the end of the cycle of operation after closing of the door 106. The means 19 includes a pivoted lever 120 having an arm 121 extending upwardly to a point adjacent the switch B. A helical spring 122 is arranged between the lever arm 121 and the lever 52 of the switch B. A stem or pin 123 may be provided to guide or prevent displacement of the spring 122. A cam 124 is provided on the shaft 43 to engage or cooperate with the lower arm of the lever 120 to swing the lever arm 121 upwardly toward the switch B to compress the spring 122. The spring 122 operates to transmit force from the lever arm 121 to the operating lever 52 of the switch B to open the switch and thus stop operation of the device. It is to be understood that the cam 124 does not operate the lever 120 to open the switch B until the elephant's head or part 13 is returned to its normal position and the door 106 is closed. The momentum of the moving parts causes the cam 124 to pass out of engagement with the lever 120 after opening of the switch B and brings the parts to their normal idle positions preparatory to another operation of the device.

The invention may include means to control movement of the coins through the chute 55 so that it may be ascertained if "slugs" or articles other than the proper coins are being used in the device. An elongate opening or slot 130 is provided in the panel 25 and extends along a substantial portion of the forward side of the chute 75

55. A piece 131 of plate glass or the like, is provided to close the forward face of the chute 55 whereby the coins in a substantial portion of the chute are visible at the front of the cabinet 5. 10. A pivoted escapement member or block 132 is provided on the inner side of the chute 55 and has two spaced pins 133 slidable through openings in the inner wall of the chute to project into the chute and engage the coins. The block 132 is carried by a pivot rod 134. A link 135 connects the pivot rod 134 with the lever 100 in a manner to cause the block 132 to be pivoted or turned once during each operation of the device. When the block 132 is turned or pivoted, one of its pins 133 moves out of the chute 155 to allow a single coin to fall through the chute into the box 56 and its other pin 133 moves into the chute 155 to prevent the other coins in the chute from moving downwardly into the box. In this manner the pins of the block 132 always retain a number of the last-used coins in the visible portion of the chute 55 so that the attendant may readily ascertain if the proper coins are being used to operate the device.

25. It is believed that the operation of the vending machine or amusement device provided by the present invention will be readily understood from the foregoing detailed description. The part 13 or elephant's head, and the various other 30 parts of the mechanism are normally in the positions illustrated throughout the drawings. Upon a player passing a coin into the chute 55 by means of the slide 54, the inner end of the slide cooperates with the operating pins 57 and 58 of the switches A and B to open the switch A and close the switch B. This, of course, does not cause energization of the motor 42 and the device cannot be made to operate until the slide 54 is returned or is permitted to return to its 35 normal out position. The coin deposited in the slide 54 falls into the chute 55 to roll or pass downwardly therethrough under the control of the escapement pins 133 as just described. When the slide 54 returns to its normal position, the hook 59 engages the pin 57 of the switch A to close the switch A. The switch B remains closed after the slide 54 has been pushed in so that closing of the switch causes energization of the motor 42. The motor, through the geared drive 44 40 slowly rotates the shaft 43, causing the cam 62 to operate the lever 60 downwardly. Downward swinging of the lever 60 pulls the flexible element 64 and moves the elephant's head or part 13 across the table 12 and at the same time causes the lever 61 to swing upwardly. As the elephant's head or part 13 moves forwardly across the table 12 it may engage an article or articles on the table and if desired or found necessary, the player may turn the knob 80 to move the rear 45 end of the rail 36 in either direction through the slot 38 and thus partially control the direction of movement of the part 13. The part 13 moves forwardly to a position at the inner edge of the opening 30 and may push an article or articles from the table 12 on to the door 96. After the elephant's head or part 13 has reached its fully forward position, the cam 63 cooperates with the lever 61 to swing the lever downwardly and cause the part 13 to return to its normal position and to cause the lever 60 to pivot upwardly to its 50 normal position.

55. After the elephant's head or part 13 has reached its fully forward position at the opening 30, the cam 104 comes into engagement with the lever 100 causing the lever to release the latch 98 and

cooperate with the cam 103 and swing the door 96 downwardly to its open position. The article or articles on the door 96 are free to fall through the chute 11 to the door 106. After opening of the door 96 the cam 104 moves out of engagement with the lever 100 allowing the lever and the door 96 to return to their closed positions. The latch 98 automatically latches the door 96 closed. When the door 96 has been closed, the cam 113 comes into cooperation with the lever 109 to move the arm 110 of the lever upwardly from between the post 111 and the edge of the door 106, and then swings the door 106 to its open position allowing the article or articles to fall to the accessible lower portion 31 of the chute. Simultaneously with opening of the door 106, the lever extension 119 moves out of engagement with the contact arm 117 of the switch M allowing the switch M to open. Prior to opening of the switch M the cam 104 moves into 10 cooperation with the contact arm 117 of the switch N to close the switch N. The switch N is held closed by the cam 104 until the cam 113 moves out of engagement with the lever 109 to 15 allow closing of the door 106 and closing of the switch M by the lever extension 119. If the player holds the door 106 open in an attempt to interfere with the operation of the door, the cam 104 will move out of cooperation with the contact arm 117 of the switch N in the proper sequence and thus break the circuit C to stop 20 the operation of the device. Attempts to start the motor 42 by inserting coins by means of the slide 54 while holding the door 106 open will not be successful as the switch M remains open until the door 106 is permitted to close. Under 25 normal operating conditions where the movement of the door 106 is not interfered with the cam 104 holds the switch N closed until the door 106 is returned to its closed position by the spring 114 and the lever 109 returns to its normal position to lock the door 106 and to close the switch M. The cam 104 then moves out of engagement with the contact arm 117 of the switch N and the cam 124 comes into cooperation with the lever 120. The cam 124 pivots the lever 120 to cause compression of the spring 122 and opening of the switch B. The switch B thereafter remains open until the slide 54 carrying a coin is pushed inwardly. The parts of the mechanism are in 30 their approximate normal position upon opening of the switch B and their momentum carries them to their normally idle position when the motor 42 is de-energized. The means 17 causes the table 12 to be turned a part of a revolution 35 during the latter part of the cycle of operation of the device. Turning of the table 12 changes the positions of the articles on the table with respect to the part 13 so that the player cannot accurately anticipate the positions of the articles with respect to the part 13. The baffle 95 prevents the prizes or articles on the table from assuming 40 positions adjacent the edge of the table and prevents the articles from becoming too closely grouped together. It is to be noted that the present invention provides an amusement device that is entirely tamper proof and that is amusing and entertaining.

Having described only a typical form and application of my invention, I do not wish to be restricted or limited to the specific form and application herein set forth, but wish to reserve to myself any modifications or variations that may appear to those skilled in the art or fall within the scope of the following claims.

Having described my invention, I claim:

1. An amusement device including, a support for carrying articles, a part supported for movement across said support substantially in parallelism therewith to push articles therefrom, and coin controlled power means for moving said part.
2. An amusement device including, a support for carrying articles, a part for engaging the articles, means supporting said part for movement across said support in relatively close proximity thereto, power actuated means for moving said part across the support to push articles therefrom and then back to its normal position, and manual means for governing the direction of movement of said part.
3. An amusement device including, a support for carrying articles, a chute having its receiving end adjacent an edge of the support, a part for engaging the articles, means supporting the part for movement across the support toward said end of the chute and only in a plane substantially parallel with the support to push articles from the support to the chute, means for operating the part, and closure means for the chute actuated by the last mentioned means.
4. An amusement device including, a support for carrying articles, a chute having its receiving end adjacent an edge of the support, a part for engaging the articles, means supporting the part for movement across the center portion of the support toward said end of the chute and in relatively close proximity to the support to push articles from the support to the chute, and power actuated means for operating the part toward the chute and for returning the part to its normal position.
5. An amusement device including, a support for carrying articles, a chute having its receiving end adjacent an edge of the support, a part movable across the support toward said end of the chute and operable to displace articles from the support to the chute, means for operating the said part toward the chute and for returning it to the normal position, a normally closed closure for the chute, means for opening said closure, and power means for actuating said means.
6. An amusement device including, a support for articles, a part movable across the support in a plane substantially parallel therewith and operable to push articles from the support, mechanical means for operating the said part in one direction, and manually operable means for moving the part laterally in said plane relative to said direction of movement.
7. An amusement device including, a support for articles, a part movable across the support and operable to push articles from the support, a power means having an energizing circuit, a coin controlled starting switch in the circuit, means actuated by the power means for operating said part, a chute for receiving articles pushed from the support by the said part, a normally closed closure for the chute, and means operable by the power means for opening said closure and operable to keep the circuit open if said closure is tampered with.
8. An amusement device including, a support for articles, a part movable across the support and operable to push articles from the support, a chute for receiving articles pushed from the support by said part, a normally closed spring held closure for the upper end of the chute, means for moving the said part toward the receiving end of the chute and then returning it to the normal position, means for opening the closure subsequent to the movement of the part toward the chute, and power driven means for actuating said means.
9. An amusement device including, a rotatable table for carrying articles, a part movable over the central portion of the table and operable to push articles from the table, means moving said part and for returning it to a normal position, and means for turning the table.
10. An amusement device including, a rotatable table for carrying articles, a chute having its receiving end adjacent an edge of the table, a part movable substantially diametrically across the table toward and away from the chute and operable to push articles from the table into the chute, means for moving said part to a position adjacent the receiving end of the chute and then returning it to its normal position, and means for turning the table subsequent to the movement of the part toward the chute.
11. An amusement device including, a rotatable table for carrying articles, a chute having its receiving end adjacent an edge of the table, a part movable toward and away from the chute and operable to push articles from the table into the chute, means for moving said part to a position adjacent the receiving end of the chute and then returning it to its normal position, a closure for the chute, means turning the table, and means for opening the closure subsequent to the movement of the part toward the chute.
12. An amusement device including, a support for carrying articles, a chute having its receiving end adjacent an edge of the support, a part movable across the support toward said end of the chute and operable to displace articles from the support to the chute, a normally closed closure for said end of the chute, a normally closed closure in the chute below said end, means for moving said part forwardly to a position at said end of the chute and for returning said part to its normal position, means for opening the first mentioned closure subsequently to the forward movement of said part, means for closing the first mentioned closure, and means for opening the second mentioned closure subsequently to the closing of the first mentioned closure.
13. An amusement device including, a support for articles, a part movable across the support and operable to push articles from the support, a power means having an energizing circuit, a coin controlled starting switch in the circuit, means actuated by the power means for operating said part, a chute for receiving articles pushed from the support by the said part, a closure for the upper end of the chute, a closure in the chute below the first mentioned closure, two switches in the circuit normally tending to open, means normally locking the second mentioned closure and closing one of said switches and operable by the power means to open the second mentioned closure and allow said switch to open, means for automatically closing the second mentioned closure and for returning the last mentioned means to its normal condition, and means operable by the power means for opening the first mentioned closure prior to opening of the second mentioned closure and for closing the said other switch during the period the second mentioned closure is open.
14. An amusement device including, a table for carrying articles, a chute having its receiving end adjacent the table, a rail spaced above the table and extending in the direction of the chute, means

5 pivotally supporting one end of the rail, means supporting the other end of the rail for lateral movement, a trolley operable on the rail, a part on the trolley operable to push articles from the table into the chute, mechanical means for operating the trolley along the rail and manual means for pivoting the rail.

10 15 20 15. An amusement device including, a table for carrying articles a chute having its receiving end adjacent the table, a rail spaced above the table and extending in the direction of the chute, means pivotally supporting the end of the rail adjacent the receiving end of the chute, means supporting the other end of the rail for horizontal movement, a trolley movable longitudinally on the rail, a part on the trolley operable to push articles from the table into the chute, power operated means for moving the trolley along the rail to the chute and for then returning the trolley, manually operated means for moving the rail horizontally.

25 30 16. An amusement device including, a support for articles, a part movable across the support and operable to push articles from the support, a power means having an energizing circuit, a coin controlled starting switch in the circuit, means actuated by the power means for operating said part, a chute for receiving articles pushed from the support by the said part, a normally closed closure for the chute, means operable by the power means for opening said closure and operable to

keep the circuit open if said closure is held open, means for automatically closing said closure, and means for automatically opening the starting switch after said closure is closed.

17. An amusement device including a cabinet, a horizontal partition in the cabinet having a vertical opening, a rotatable table closing the lower end of said opening and adapted to support articles, there being an opening in the partition joining the first mentioned opening and adapted to pass articles pushed from the table, a part movable across the table and operable to push articles into the last mentioned opening, automatic means for operating said part toward and away from the last mentioned opening, and manual means for governing the direction of movement of the said part. 5 10 15

18. An amusement device including a cabinet, a horizontal partition in the cabinet having a vertical opening, a rotatable table closing the lower end of said opening and adapted to support articles, there being an opening in the partition joining the first mentioned opening and adapted to pass articles pushed from the table, a part movable across the table and operable to push articles into the last mentioned opening, automatic means for turning the table, and a baffle projecting across the table to prevent the articles from assuming positions adjacent the periphery of the table. 20 25
